CRANKCASE VENTILATING SYSTEM

William Engstrom, Muskegon, and Earl Ginn, North Muskegon, Mich., assignors to Continental Motors Corporation, Muskegon, Mich., a corporation of Virginia

Application August 14, 1940, Serial No. 352,572

6 Claims. (Cl. 123—119)

Our invention relates to internal combustion engines and more particularly to a crankcase ventilating system and the like embodying a passage connecting the crankcase with the engine induction system which includes a unit structure comprising a housing having a restricted passage and a metering element associated preferably with said restricted passage and operating in said housing.

Prior devices which are designed to ventilate an engine crankcase, embody constructions which are not readily serviced and which do not lend themselves to production manufacture.

An object of our invention is to construct an improved crankcase ventilator system by incorporating therein a unitary ventilating metering means which is adaptable for production assembly with an internal combustion engine.

More particularly, our invention has for its object the provision of a ventilating metering means or element constructed to be carried by an engine part and in which the housing thereof is formed in part by a portion of the engine assembly, and in which the housing is provided with oil baffling means therein, and is so constructed as to guide the metering element in order to insure efficient operation at all times.

Further objects of our invention are to provide an improved device of the character described by incorporating in an engine crankcase ventilating system an improved ventilating metering element and housing assembly embodying improved details of construction which provide for a more efficiently operating device.

For a more detailed understanding of our invention reference may be had to the accompanying drawings illustrating in detail various improved features of our improved crankcase ventilating system, and in which:

Fig. 1 is a side elevational view of an internal combustion engine equipped with our improved crankcase ventilating system.

Fig. 2 is a vertical fragmentary sectional view through an engine showing our ventilating metering element and housing assembled as a unit with a valve chamber cover.

Fig. 3 is a detail fragmentary sectional view taken substantially on the line 3—3 of Fig. 2.

Fig. 4 is a horizontal sectional view through the ventilating metering element housing and taken substantially on the line 4—4 of Fig. 3.

Fig. 5 is a vertical sectional view taken substantially on the line 5—5 of Fig. 3 and showing the metering element and housing and illustrat-

ing the manner of attaching same to the valve chamber cover.

Fig. 6 is a fragmentary vertical sectional view similar to Fig. 5 showing the ventilating metering element in another position.

Fig. 7 is a fragmentary detail sectional view of the ventilating device including the housing, showing in detail the action of the oil baffling means, and which is taken substantially on the line 7—7 of Fig. 5.

Fig. 8 is a detail perspective view of a weighted ventilating metering element.

Fig. 9 is a detail sectional view showing a modified construction.

Fig. 10 is a detail sectional view taken on the line 10—10 of Fig. 9, and

Fig. 11 is a fragmentary sectional detail view of a further modified construction.

Our crankcase ventilating system is constructed for assembly with an internal combustion engine 10 of substantially standard construction which includes a cylinder block 11, a cylinder head 12, water connection 13, a crankcase 14, exhaust manifold 15, and an intake manifold 16 which is preferably connected with a suitable fuel mixture and forming device or carburetor 17. The cylinder block is preferably provided with a valve chamber 18 having an opening 19 which is closed by a conventional valve chamber cover 20. The crankcase 14 encloses a crankcase chamber 21 of usual construction which is placed in communication with the valve chamber by means of a port or passage 22.

For some time, engines have been constructed with crankcase ventilating systems which utilize the suction pressure of the engine induction system for withdrawing vapors from the crankcase, said crankcase being preferably provided with an air intake means 23 which may if desired, have an air-cleaner device 24 associated therewith so as to admit relatively clean air to the crankcase. Our improved crankcase ventilating system embodies a unitary device which is carried on an engine part and preferably by a removable engine part such as the valve chamber cover 20. Our improved device embodies a housing 25 which is preferably formed of a die-casting and is secured by means of screws or other suitable fastening devices to the inside face of the valve chamber cover, said cover being preferably formed with a bossed portion 27 in which the housing 25 is seated. It will thus be noted that the valve chamber cover thus forms a part of the housing, a suitable gasket 28 being clamped between the housing and valve chamber cover.

The housing is provided with an outlet duct 29 opening through the open face of the housing and arranged to be connected with a union or coupling 30 which is in turn connected to a conduit 31 connected with the engine intake manifold as at 32. A passage 33 connects the outer fold 29 with the interior chamber 34, and the housing is provided with a partition wall 35 intermediate the chamber 34 and the inlet 36, which wall serves as an oil baffling means, since the incoming gases are forced to turn as indicated by the arrows 37 and 38 when flowing through the device from the inlet towards the outlet.

A restricted passage is essential to the operation of a crankcase ventilating system, and same is preferably located somewhere in the line connecting the crankcase with the engine intake manifold. Such a restricted passage or orifice, as is required to make an operative structure, will very easily become clogged with sludge or other foreign matter and it is therefore the practice to provide a clean-out device operating in the system restricted passage, the movement of the clean-out device maintaining the restricted passage substantially free of sludge and preventing same from becoming clogged. It is customary to provide these clean-out devices with a weight and subject the device to the pulsating pressures of the engine induction system to move the clean-out device axially of the restricted passage in order to prevent sludge from accumulating in said restricted passage. Many failures in the past, in the operation of crankcase ventilating systems heretofore employed, have been due for the most part to the inefficient operation of said clean-out devices, as they become displaced and thus are inoperative or same become jammed in the restricted opening. In the present device we have provided a crankcase ventilating device as a metering element 40 which comprises a stem 41 and a weighted portion 42, this weighted portion comprising an inverted U-shaped bracket having depending side walls or legs 43. This weighted portion of the element is of such a construction as to be guided in the chamber 34 by the housing walls, and thus is avoided any possibility of the stem portion becoming displaced and out of registration with the passage 33 in which it operates. It will be further noted that the side walls or legs 43 and preferably that one to the left as illustrated in Fig. 7 form an additional baffling means within the housing. Furthermore the housing is provided with suitable integral lugs 45, which serve as stops for limiting the upward travel of the valve element.

The housing has a hole 46 aligned with passage 33 which makes possible the admittance of a drill or other tool in the machining of the hole or passage 33. However, the area of this hole 46 is very much less than the area of the intake opening 36, and thus most of the vapors from the crankcase are drawn into the housing through the intake 36.

It will be observed that by providing this oil baffling means within the housing that much of the troubles of sludge removal are eliminated, since the heavier particles and oil particles carried by the crankcase vapors are separated and removed before said vapors are conducted to the restricted passage 44, and thus only the lighter vapor is carried into the engine induction system. The oil and heavier particles which are removed

from these oil vapors are permitted to accumulate and to be discharged through the opening 46 into the valve chamber 18.

In Figs. 9 and 10 we have illustrated a modified construction which comprises a housing 50 for the ventilating device, same being provided with an outlet 51 and intakes 52. A hollow pin 53 is slidably supported within the hole 54 of said housing and the outlet passage 51 is in open communication with the hole 54 and the interior bore 55 of the pin.

A relatively large diameter weighted hollow sleeve structure 70 is secured as by a press fit to the lower end of the hollow pin 53 and is provided with an opening 56 on its lower side which is of slightly larger diameter than the solid pin 53a so as to provide a restricted passage 57 for admitting the crankcase vapors to the interior chamber 58 within said sleeve structure 70, which chamber communicates with the bore 55 of the pin and thus with the outlet 51. The pressure pulsations in the intake manifold are communicated through the outlet passage 51, passage or hole 54, to the top face of the hollow pin 53 which carries the weighted member 70, and thus causes same to be moved up and down on the pin 53a to keep the restricted passage 57 substantially free of sludge formations.

In Fig. 11 we have illustrated a modified construction which is somewhat similar to the construction illustrated in Figs. 1 to 8 inclusive, the only difference being that the clean-out pin is stepped as at 60 to provide a variable metering element so that when the clean-out device is subjected to low vacuum pressures insufficient to overcome the gravity of the weighted portion, the restricted passage 61 is substantially larger in area. As the vacuum pressure is increased the element is lifted and the larger diameter portion 62 of the stem enters the passage 63 and thus provides a restricted passage of smaller area. The weighted portion 64 is constructed to be guided by the housing 65 so as to accurately center the stem portion of the metering element with respect to the passage 63 and thereby prevent at all times any danger of the shoulder of the stem catching on the edges of the opening 63.

This guiding means of the valve is equally important, when used with a plain stem as illustrated in Fig. 8 as the stem 41 is substantially centered with respect to the passage 33.

It will be apparent to those skilled in the art to which my invention pertains, that various modifications and changes may be made therein without departing from the spirit of my invention or from the scope of the appended claims.

We claim:

1. In an internal combustion engine having a crankcase and an induction system, and wherein the crankcase and induction system are in communication at all times through a restricted passage and are subject to varying pressure pulsations in the engine induction system tending to produce varying flow through said restricted passage, a clean out metering element displacing a part of the cross-sectional area of said passage and having a stem portion and a U-shaped weighted portion, and a housing for said element and provided with guides acting directly on said weighted portion only to restrain movement of the element to an axial movement substantially concentrically in said passage.
2. In an internal combustion engine having a crankcase and an induction system, and wherein

75

the crankcase and induction system are in communication at all times through a restricted passage and are subject to varying pressure pulsations in the engine induction system tending to produce varying flow through said restricted passage, a clean out metering element displacing a part of the cross-sectional area of said passage and comprising a stem portion and an inverted U-shaped weighted portion, said weighted portion operable externally of said restricted passage, and a housing for said element and weighted portion, said housing provided with guides directly engaging said weighted portion only and restraining movement of the stem portion of said element to an axial movement substantially concentrically of said passage, said element including the weighted portion and said housing comprising a unitary assembly.

3. In an internal combustion engine having a crankcase and an induction system, and wherein the crankcase and induction system are in communication at all times through a restricted passage and are subject to varying pressure pulsations in the engine induction system tending to produce varying flow through said restricted passage, a clean out metering element displacing a part of the cross-sectional area of said passage and having a weighted portion, and a housing for said element and weighted portion, said housing provided with guides acting directly on said weighted portion to restrain movement of the element to an axial movement substantially concentrically in said restricted passage, said element comprising an inverted U-shaped weighted portion and a stem portion secured to said weighted portion, said stem portion operable at all times in said restricted passage and having a cross-sectional area less than the cross-sectional area of said passage.

4. In an internal combustion engine having a 40 crankcase and an induction system, and wherein the crankcase and induction system are in communication at all times through a restricted passage and are subject to varying pressure pulsations in the engine induction system tending to produce varying flow through said restricted passage, a clean out metering element displacing a part of the cross-sectional area of said passage and having a weighted portion, and a housing for said element and provided with guides acting directly on said weighted portion to restrain movement of the element to an axial movement substantially concentrically in said restricted passage, said element including a stepped stem portion constructed and arranged for axial movement substantially concentrically of said passage, only said stem portion of lesser cross-sectional

area operable in said passage in response to predetermined minimum pressure pulsations in the engine induction system.

5. In an internal combustion engine having a 5 crankcase and an induction system, and wherein the crankcase and induction system are in communication at all times through a restricted passage and are subject to varying pressure pulsations in the engine induction system tending to produce varying flow through said restricted passage, a clean out metering element displacing a part of the cross-sectional area of said passage and having a weighted portion, and a housing for said element and provided with guides acting directly on said weighted portion to restrain movement of the element to an axial movement substantially concentrically in said passage, said element including a stepped stem portion constructed and arranged for axial movement substantially concentrically of said passage, only said stem portion of lesser cross-sectional area operable in said passage in response to predetermined minimum pressure pulsations in the engine induction system, and said stem portion of greater cross-sectional area operable in said passage in response to maximum pressure pulsations in the engine induction system.

20 6. In an internal combustion engine having a crankcase and an induction system, and wherein the crankcase and induction system are in communication at all times through a restricted passage and are subject to varying pressure pulsations in the engine induction system tending to produce varying flow through said restricted passage, a clean out metering element displacing a part of the cross-sectional area of said passage and having a weighted portion, and a housing for said element and provided with guides directly acting on said weighted portion to restrain movement of the element to an axial movement substantially concentrically in said passage, the said 30 metering element comprising an inverted U-shaped weighted portion and a stem portion secured to said weighted portion, said stem portion operable at all times in said passage and having a cross-sectional area less than the cross-sectional area of said passage, and stop means comprising lugs depending from the top internal wall of the housing and engaging the top plane surface of said U-shaped weighted portion to prevent said weighted portion from closing said passage when said element is subjected to maximum pressure pulsations of the engine induction system.
